Filed May 4, 1959, Ser. No. 810,716

10 Claims. (Cl. 62—137)

This invention relates to improvements in ice makers and more particularly relates to an improved form of automatic ice maker for use in household refrigerators.

A principal object of the invention is to provide a simplified form of ice maker of the self-releasing rotatable tray type arranged with a view toward utmost simplicity and efficiency in operation and control.

Another object of the invention is to provide a simplified form of ice maker of the self-releasing rotatable tray type in which a metering device is provided to fill the molds with a measured volume of water, and in which the pressure of the water filling the metering device supplies the pressure to rotate the molds to accommodate the release of ice cubes therefrom by the heat of the water filling the empty molds.

Still another object of the invention is to provide an ice maker of the rotatable type in which control of the freezing and releasing of the ice pieces is by a thermal element and an electric heater therefor, in which the power for rotating the ice tray to bring the tray into position to release the ice pieces therefrom, is attained by the filling of a metering device, metering water to fill the empty ice molds, and in which an ice level sensing arm movable vertically during each cycle of rotatable movement of the molds, controls operation of the ice maker and effects the continued cycle of the ice maker until the storage basket for the ice pieces is full.

Still another object of the invention is to provide a simplified form of ice maker of the rotatable tray type in which one ice mold faces in a direction to discharge frozen ice pieces therefrom when the other ice mold is in position to be filled with water, in which the ice mold is oscillatably driven under the control of a thermostat sensing the freezing of the water into ice pieces, and in which the instigation of oscillatable movement of the mold is controlled by an ice level sensing arm, continuing the ice making operation and retaining the thermostat from instigating an operation of oscillatably moving the mold, when the storage basket for the ice pieces is full.

These and other objects of the invention will appear from time to time as the following specification proceeds and with reference to the accompanying drawings wherein:

Figure 1 is a view in side elevation of an ice maker constructed in accordance with the invention, with certain parts broken away and certain other parts shown in vertical section;

Figure 2 is a fragmentary end view of the ice maker shown in Figure 1, looking at the ice maker toward the opposite end thereof from the drive mechanism therefor;

Figure 3 is a fragmentary rear end view of the ice maker illustrating the drive mechanism therefor and showing the metering device, supplying the power to drive the ice maker, in vertical section;

Figure 4 is a fragmentary view in side elevation of the rear end portion of the ice maker, showing certain parts of the drive mechanism not shown in Figure 3;

Figure 5 is a view in side elevation of the metering de-

2

vice and the drive mechanism driven thereby, and forming in effect a continuation of Figure 4;

Figure 6 is a view in side elevation of the thermally responsive actuator, controlling operation of the ice maker;

Figure 7 is a transverse sectional view taken substantially along line 7—7 of Figure 6 and illustrating certain details of the thermally responsive actuator not shown in Figure 6; and

10 Figure 8 is a schematic wiring diagram showing a circuit diagram for effecting operation of the ice maker and carrying the ice maker through its ice making cycles.

In the embodiment of the invention illustrated in the drawings, I have shown in Figures 1 and 2 a storage basket 10 for frozen ice pieces. The storage basket 10 has an open top having a rotatable freezing receptacle or ice tray 11 extending therealong and mounted thereabove. As shown in Figures 1 and 6, the ice tray 11 is oscillatably mounted on a shaft 15, rotatably mounted in a bearing boss 16 extending from an attachment flange 17 of a thermally responsive actuator 19. The attachment flange is shown in Figure 1 as being mounted on a rear wall 20 of the refrigerator cabinet. The thermally responsive element also has a forwardly spaced flange 21 abutting an inwardly spaced wall 22 of the refrigerator cabinet.

30 The ice tray 11 is constructed on principles similar to those shown and described in an application Serial No. 740,898, filed June 9, 1958, now Patent No. 2,939,298, by Carl C. Bauerlein and entitled "Self-Releasing Ice Mold."

35 The ice tray 11 is shown as being generally triangular in form, having two sets of oppositely facing molds 23 having a common radial wall 24 in heat conductivity with each set of molds. The molds 23 have outer wall portions 25, shown in Figure 2 as extending inwardly toward the center of rotation of the tray at equal angles with respect to a radial line extending through the center of rotation of the tray and the centerline of the wall 24.

40 Partitions or dividers 26 extend between the common radial wall 24 and the insides of the outer wall portions 25 to divide the tray into the molds 23, herein shown as being a series of individual prism like molds. The dividers 26 are tapered from the inner to the outer ends 45 thereof to provide ice prism molds diverging outwardly from the bottom of a particular mold to the top, when the mold is in the water receiving position shown in Figure 2, and diverging outwardly and downwardly when the particular mold has been rotated to an ice releasing 50 position.

55 The wall portions 25 are shown as terminating into drip troughs or retainers 29, extending along the outer edges thereof to collect the drops of water dropping from the thawing surfaces of the ice prisms, as the ice prisms are released by the heat of the water filling the upwardly facing molds, and to return the water to the molds when the tray is turned to position the molds 23 into a position to be filled, it being understood that the heat of the water filling the molds thaws the frozen water in the troughs or drip retainers 29. The drip retainers 29 are shown as being spaced in advance of the ends of the partitions 26 to accommodate the flow of water from one mold to the other, as one mold is filled, and to thereby accommodate the use of a single spout 30, supplied with water by a liquid measuring device 31, to successively fill the individual ice molds.

60 Drying racks in the form of parallel spaced bars 33, spaced beneath the ice tray 11 and extending along each side thereof, are provided to cooperate with the drip retainers 29, to support the released ice prisms during freezing of the water in the upwardly facing molds, and to thereby accommodate the wetted surfaces of the

ice prisms, thawed by the heat of the water filling the molds, to dry by freezing, as the water in the upwardly facing ice molds freezes. As the water freezes in the upwardly facing molds 23 and the tray is turned to bring an empty set of ice molds 23 into position to be filled with water, the ice prisms will be released from the drying rack 33 and drip retainer 29, to fall into the storage basket 10 in a dry condition.

An end wall 35 of the ice tray 11, adjacent the thermally responsive actuator 19, has a camming lug 36 projecting therefrom and shown in Figure 2 as having its center in alignment with a radial line extending through the axis of rotation of the mold and the center line of the wall 24. The camming lug 36 projects toward the thermally responsive actuator 19 and engages the underface of a pivoted follower 37, suitably secured to a transverse shaft 39. The transverse shaft 39 is shown in Figures 1 and 2 as having an angularly and downwardly turned portion 40 having a horizontally extending lower end portion 41 having an ice level sensing shoe 43, mounted thereon and extending therefrom.

The lower face of the follower 37 is shown as being relatively wide and as being engaged by the camming lug 36, as the ice tray 11 moves from the solid line position shown in Figure 2 to the dotted line position shown in this figure, in one direction of movement of the ice tray, and from the dotted line position to the solid line position shown, in an opposite direction of movement of the ice tray, to raise and lower the ice level sensing shoe 43 each time the ice tray is moved into position to accommodate the discharge of ice cubes therefrom. When the storage basket 10 is filled with ice pieces to a predetermined level, the ice level sensing shoe 43 will be held in an elevated position and prevent the recycling operation of the ice maker.

As shown in Figures 1, 2 and 7 a cam 44 is mounted on the shaft 39, and is oscillatably moved by said shaft. The cam 44 has a cam face 45 engaging the outer end portion of a plunger 46, slidably mounted within a housing 47 for the thermally responsive actuator 19. The plunger 46 is shown as being sealed to a cover 49 of the thermally responsive actuator by a flexible diaphragm 50, and as having an inner end portion 51 engaging an outwardly extending spring arm 53 extending outwardly from a resilient catch 55, engaging an over center lever 56 of the thermally responsive actuator, to hold said lever from operating to engage a movable switch arm 57 with a stationary contact 59, upon retractable movement of a piston 60 of a thermally responsive element 61, and to thereby prevent turning of the ice tray 11 into a discharge position, when the storage basket 10 is filled with ice pieces.

The thermally responsive actuator is similar to that shown and described in my joint application with Donald E. Miller, Serial No. 801,087, filed March 23, 1959, and entitled "Analog Thermostat," so need only be described herein insofar as is necessary to render my present invention clearly understandable. The thermally responsive element 61 is a well known form of power or high motion solid fill type of thermally responsive element, in which a fusible thermally expansible material within a casing 63, acts against a flexible membrane or diaphragm (not shown), to extensibly move the power member or piston 60 from a cylinder 64, upon fusion of the thermally expansible material.

The thermally responsive element 61 is mounted on the bottom of a cage 65 forming a support for the stationary contact 59 and the movable switch arm 57. An annular spring retainer 66 is mounted in the cage 65 and forms a seat for a return spring 67 for the piston 60. The return spring 67 is shown as being a conical spring, seated at one end in the retainer 66, and seated at its opposite end on saddle 69, mounted on the piston 60 and extending outwardly and angularly inwardly therefrom toward the bottom of the cage 24.

The casing 63 of the thermally responsive element 61 is enclosed by a generally cylindrical container 70, spaced from said casing in radial and axial directions and abutting the bottom of the cage 65 and suitably secured thereto in water tight relation with respect thereto. The container 70 forms a chamber, filled with water or a like freezable material having similar variations of temperature with time as the water in the ice tray 11. The container 70 has a tube 71 of low heat conductivity extending from the bottom thereof through the cover 49 for the housing 47 and extending toward the ice tray 11 in the evaporator compartment of the refrigerator. The tube 71 is closed at its outer end by a plug 72, which may be of high heat conductivity. The plug 72 and tube 71 retain ice crystals therein upon melting of the water in the container 70 which serve to seed the water in the container 70 with ice crystals and inhibit supercooling thereof as in my joint application with Donald E. Miller, Serial No. 801,087.

The container 70 is encircled by a resistor heater 73, which serves to heat the water in the container 70 and reset the thermally responsive element, to effect extensible movement of the piston 60.

The switch arm 57 extends through a slot (not shown) 25 in a slotted leg 74 of a terminal 75, mounted in and extending outwardly of an insulating plate 76, suitably mounted in the cage 65. The over center lever 56 is also 30 rockingly mounted in the slotted leg 74 and abuts the end of the piston 60 and is rocked thereby in one direction upon extensible movement of said piston. A tension spring 76, connected between the outer end portion of an arm 77 of the over-center lever 56 and the insulator plate 78, is provided to bias the over-center arm 56 into engagement with the end of the piston 60. The switch arm 41 also extends through a slotted portion (not shown) 35 of the arm 74, to be moved by said arm out of engagement with the stationary contact 59 into engagement with a stationary contact 80, upon increases in temperature effected by energization of the resistor heater 73. The contact 59 is mounted on an inwardly extending end portion 40 81 of a terminal 83, mounted in the insulating plate 78 and extending outwardly therefrom. The contact 80 is likewise mounted on the inner end portion of a terminal 45 84, mounted in the insulating plate 78 and extending outwardly therefrom.

During each cycle of operation of the icemaker, as the ice pieces are discharged from the ice tray 11 into the storage basket 10, the over-fill shoe 43 will be raised by the camming lug 36. This will effect movement of the cam 44 in a clockwise direction from the position shown in Figure 7 and accommodate outward movement of the plunger 46 to follow the cam face 45 by the bias of the spring 53. The catch 55 will at the same time be moved into the position shown in Figure 7, in position to catch the end of the over-center lever 56 and prevent engagement of the switch arm 57 with the stationary contact 59 when the piston 60 has been extended by increases in temperature of the thermally responsive element, effected by energization of the resistor heater 73, and is then retracted by the return spring 67 upon deenergization of said resistor heater and freezing of the water in the tray 11. As the ice tray 11 continues its rotatable movement to the discharge position shown by dotted lines in Figure 2, the sensing shoe 43 will then drop, moving the cam 45 in a counterclockwise direction and depressing the plunger 45 and moving the catch 55 out of position to engage the end of the over-center arm 56, and to therefore accommodate the recycling of the icemaker.

When, however, the storage basket 10 is filled with ice pieces to a level which will prevent dropping of the ice level sensing shoe 43, the resilient arm 53 will extend the plunger 46 with respect to the housing 47. The resilient catch 55 will be in the position shown in Figure 7 to engage the over-center arm 56 and prevent the engagement of the switch arm 57 with the stationary contact 59, until

the sensing shoe 43 again drops by the removal of ice pieces from the storage basket 10.

Referring now to the metering device 31 and the means for oscillatably driving the ice tray 11, said metering device may be mounted on a back wall of the refrigerator and is similar to that shown and described in the aforementioned Bauerlein application Serial No. 763,254, so need only herein be described in sufficient detail to render my present invention readily understandable.

The metering device 31 includes a casing 85 having a piston 86 movable therealong. A piston rod 87 extends from the piston 86 and is slidably guided in an upper end wall 88 of the casing 85 and has rack teeth 89 thereon, meshing with a gear 90 on a transverse shaft 91 suitably mounted on the housing 85.

A diaphragm 93 is mounted within the casing 85 and has an annular rim 94 sealed to a flanged portion 95 of an upper half 96 of the casing 85 by a clamping ring 98, clamping a lower half 97 of the casing 85 into engagement with the marginal rim of the diaphragm 93. The diaphragm 93 is of a generally cylindrical form and has a closed bottom abutting the inner end of the piston 86 and with the interior wall of the casing forms a measuring chamber. A spring 99 seated on the end wall 88 and engaging the piston 86 is provided to retractably move said piston and force a measured amount of fluid through an outlet 100 from the metering device.

As water in the ice tray 11 freezes, the return spring 67 will engage the contact arm 57 with a contact 59. This will energize a solenoid coil 101 of the metering device 37 and withdraw a valve 103 on the inner end of an armature 104 from a pilot port 105, leading through a diaphragm valve 106 and will accommodate water under pressure in an inlet 107 to move the diaphragm valve 106 off its seat, and flow into the metering chamber through an inlet passageway 109. Water entering the inlet passageway 109 will force the diaphragm 93 and piston 86 to move toward the wall 88 against the bias of the spring 99 and thereby increase the volume of the metering chamber to the end of travel of the piston 86, to contain a slug of water of a volume sufficient to fill the upwardly facing molds 23 in the ice tray 11.

When it is desired to meter a slug of water into the molds 23 of the ice tray 11 through the filler spout 30, the solenoid coil 101 is deenergized and a solenoid coil 111 is energized under the control of the switch arm 57 and the thermally responsive actuator 19, as will hereinafter more clearly appear as this specification proceeds.

This will withdraw a valve 112 on the inner end of an armature 113 from a pilot port 114, and will accommodate water forced through a port 115 by the energy stored up in the spring 99 to unseat the diaphragm valve 117. A measured slug or volume of water will then flow through the outlet 100 and filler spout 30 to fill the upwardly facing ice molds 23 with water. It will also reverse the travel of the rack 89 and the gear 90.

The oscillatable drive to the shaft 15 from the rack 89 and gear 90 includes a disk 119 on the shaft 91 and driven from the gear 90 through a one-way clutch 120. The one-way clutch 120 is herein shown as being a spring clutch of a type in which a spring 121 wraps around a drum 123 in one direction of rotation of the clutch to rotatably drive the disk 119 and unwraps from the drum 123 in a reverse direction of rotation of the gear 90, as is well known to those skilled in the art, so not herein shown or described further.

The disk 119 has spaced ratchet teeth 124 formed integrally therewith and shown in Figure 3 as being spaced 180° apart. The ratchet teeth 124 are engaged by a pawl 125 holding the disk 119 from rotation in a direction opposite to the direction of said disk is driven by the one-way clutch 120.

The disk 119 has a collar 127 rotatably mounted thereon inwardly of the periphery thereof. A drive rod 128 extends transversely through the collar 127 and is

secured thereto as by a machine screw 129 threaded in the end of said collar and suitably locked to said collar. The drive rod 128 is shown as being slidably mounted in a drive member 130 slidably guided on the back wall 5 of the refrigerator. The drive rod 128 has a head 131 at its upper end, abutting a shouldered portion of the member 130 and limiting downward movement of said rod. A Bodin wire 135 extends through two facing cup-like guides 132 guided in the drive member 130 and forced apart by a spring 133, to bias the upper cup-like guide into engagement with the top of the drive member 130, and the lower cup-like guide into engagement with a shouldered portion 134 of the drive member 130. Upper and lower stops 136 and 137 on the Bodin wire 135 abut the upper and lower cup-like guides 132. Thus upon rotation of the disk 119 in a clockwise direction from the position shown in Figure 3, the rod 128 will move upwardly along the drive member 130 until the head 131 engages the end of the Bodin wire 135. The 10 Bodin wire and drive member will then move vertically, it being understood that the spring 133 normally acts as a solid member.

The Bodin wire 135 is slidably guided in a cable guide 138 extending vertically along the refrigerator wall and 25 clamped at its upper end to a collar 142 mounted on an inturned end portion 140 of a crack 139, slidably guided in a vertically extending guide 141, covered by a cover plate 143. The cover plate 143 is shown as having a bracket 144 depending therefrom having a clamp 145 for 30 the cable guide 138 mounted thereon.

The guide 141 is formed in a guide plate or housing 146 extending from the housing 47 of the thermally responsive actuator 19 and encloses a gear 147 mounted on the outer end of the shaft 15 for oscillatably driving 35 said shaft and the ice tray 11.

It will be noted with reference to Figures 3 and 5, that as the metering chamber is filled with water, that the rack 89 will be extensibly moved with respect to the casing 85 and rotate the gear 90 and disk 119 through 40 180°. This will move the collar 127 through 180°, and move the rack 139 a distance substantially equal to the distance between the centers of the collar 27 in its two extreme positions, minus the distance from the head 131 to the end of the Bodin wire 135. This will rotate the ice tray 11 through a lesser angle than the angle of rotation of the collar 127 and will bring the upwardly facing ice molds 23 and the frozen ice pieces therein into the downwardly facing discharge position shown in Figures 1, 2 and 3.

As water is metered through the outlet 100, the spring 99 will reverse movement of the rack 89, but the disk 119 will be held from rotation by the pawl 124. During the next operation of filling the metering device, the rack 89 will again be extensibly moved to rotate the 55 disk 119 through 180° and bring the collar 127 to the position shown in Figures 3 and 5.

This will reverse the direction of movement of the rack 139 and bring the upwardly facing ice molds 23 into a downwardly facing discharge position to accommodate the discharge of the ice pieces by the heat of 60 the water filling the empty molds.

A switch 150 is mounted on a guide 151 for the rack 89 and extend outwardly therefrom. The switch 150 is diagrammatically shown in Figure 8 as being a plunger type of switch and has a movable contact 153 engageable with stationary contacts 154 in a conductor 155 connected from the stationary contact 80 of the thermally responsive actuator 19 to the solenoid coil 111, to energize said solenoid coil when the switch is closed. The switch 150 is normally closed and has a switch button 156 engaged by the end of a screw 157 threaded in a right angled arm portion 159 of a control arm 160. The control arm 160 may be a continuation of the rack 89, to effect vertical movement of the screw 150 with 70 vertical movement of said rack.

Thus, when the spring 99 has moved the piston 86 and diaphragm 93 to the extreme end of its metering stroke, the screw 157 will engage the switch button 156 and move the movable contact 53 out of engagement with the stationary contacts 154 to deenergize the solenoid 111 while the switch arm 57 is in engagement with the stationary contact 80.

Referring now to Figures 1, 7 and 8 as the water in the upwardly facing molds 23 is frozen, the spring 67 will have retractably moved the piston 65 of the thermal element 61 to the position shown in Figure 7. The switch arm 57 will then engage the stationary contact 59 and a circuit will be completed through a conductor 161 to the solenoid coil 101, to energize said solenoid coil and open the valve 106 to effect filling of the metering chamber and extensible movement of the diaphragm 93 and piston 85 against the spring 99. The reset heater 73 will also be energized through a conductor 162 to start melting of the freezable liquid contained within the chamber 70 and to heat the thermally expandable material within the casing 63 to effect extensible movement of the piston 60. A resistor heater 163 coiled about a pipe 165 leading from the outlet 100 from the metering device 31 to the filler spout 30 will also be energized to heat the water in the pipe 165 prior to discharge into the ice molds 23 by energization of the solenoid coil 111.

During filling of the metering chamber, the rack 89 will be extensibly moved by the piston 86 to turn the upwardly facing ice molds 23 and the frozen ice therein into a downwardly facing discharge position, as previously described.

As the thermally responsive element 61 is heated by the resistor heater 73, the piston 60 will be extended with respect to the cylinder 64 and move the over-center arm 56 in a direction to disengage the switch arm 57 from the stationary contact 59 and to engage said switch arm with the stationary contact 80. This will take place in a time delay interval sufficient to effect the heating of the water in the pipe 131 to the required temperature to loosen the downwardly facing ice pieces from their molds. As the switch arm 57 engages the stationary contact 80, an energizing circuit will be completed to the solenoid coil 111 through the contacts 153 and 154 of the switch 150 and the conductor 155. The valve 117 will then open, the solenoid coil 101, the resistor heater 73 and the water heater 163 being deenergized upon disengagement of the switch arm 57 from the stationary contact 59. The spring 99 will then force the piston 86 and the diaphragm 93 in a retractable direction to force a measured slug of water through the outlet 100 into the pipe 165 and forcing the heated water in said pipe into the upwardly facing molds 23. When the piston 86 and diaphragm 93 have reached the end of their metering stroke, the screw 157 on the right angled arm portion 159 will have engaged the switch button 156, to open the switch 150 and deenergize the solenoid coil 111.

The upwardly facing molds 23 will then have been filled with heated water. This will loosen the ice pieces in the downwardly facing molds 23 and accommodate said ice pieces to tilt about the drip trough 29 onto the drier rack 33 and be retained in this position until freezing of the water in the upwardly facing ice molds 23 and turning of the tray 11 in a direction to bring the downwardly facing molds 23 into position to again be filled with water.

It should here be understood that each time the tray 11 is oscillated to bring the ice pieces and the upwardly facing molds into position to be discharged therefrom that the overfill shoe 43 is raised and lowered and that as the overfill shoe 43 is raised the cam 44 will move in position to accommodate the spring arm 53 to move the catch 55 into position to engage the over-center arm 56 and hold the switch arm 57 from engaging the stationary contact 59. As, however, the overfill shoe 43 is lowered, the plunger 46 will be depressed to move the catch 55 out

of position to engage the over-center arm 56 and accommodate retractable movement of the piston 60 to effect engagement of the switch arm 57 with the stationary contact 59, to effect a next succeeding ice-making operation. The overfill shoe 43 thus merely latches and unlatches the over-center arm 56 during each cycle of rotation of the ice tray 11, holding the over-center lever 56 latched only when the ice level sensing shoe 43 is held in an elevated position by ice pieces in the storage basket 10.

While I have herein shown and described one form in which my invention may be embodied, it should be understood that various modifications and variations in the invention may be effected without departing from the spirit and scope of the novel concepts thereof as defined by the claims appended hereto.

I claim as my invention:

1. In an automatic icemaker, an oscillatable tray having oppositely facing ice molds in heat transfer relation with respect to each other, metering means for filling the upwardly facing molds with a measured volume of water and loosening the ice pieces in the downwardly facing molds by the heat of the water filling the upwardly facing molds, power means actuated by the pressure of the water filling said metering means for moving said tray to bring the upwardly facing molds and the ice pieces therein in a downwardly facing release position, switch means controlling the filling of said metering means, a thermally responsive element for operating said switch means to effect filling of said metering means upon certain low temperature conditions and to effect emptying of said metering means upon certain high temperature conditions, an overfill arm sensing the level of ice pieces discharged from said molds, and means operated by said overfill arm for holding said switch means from movement to complete a circuit to effect filling of said metering means upon the discharge of a predetermined level of ice pieces.

2. In an automatic icemaker, an oscillatable tray having oppositely facing ice molds in heat transfer relation with respect to each other, a storage tray in material receiving relation with respect to said ice molds, an overfill arm having an end portion engaging the ice pieces discharged onto said storage tray, a camming connection between said ice tray and overfill arm for raising and lowering said overfill arm during each cycle of oscillatable movement of said tray, metering means for filling the upwardly facing molds with a measured volume of water and loosening the ice pieces in the downwardly facing molds by the heat of the water filling the upwardly facing molds, switch means effecting the filling of said metering means in one position, and the emptying of said metering means and the filling of said ice molds in a second position, a thermally responsive element operated by the freezing of the ice pieces, to effect movement of said switch means into one position to effect the filling of said metering means, heating means for said thermal element, heating said thermal element upon movement of said switch means to said one position, to reset said thermally responsive element and move said switch means to said second position to effect filling of the upwardly facing molds with water, and means operated by said overfill arm to hold said switch means from moving to said one position and to thereby prevent filling of said measuring device upon filling of said storage tray to a predetermined level.

3. In an automatic icemaker, an oscillatable tray having oppositely facing ice molds in heat transfer relation with respect to each other, a metering device including a metering chamber having a movable wall portion movable in one direction by the pressure of water filling said chamber and movable in an opposite direction to expel water from said chamber, means driven by said movable wall portion for rotating said tray in one direction upon one operation of filling said chamber and in an opposite direction upon a second operation of filling said chamber, a storage basket in material receiving relation with respect to said tray, a pivoted over-

fill arm movable into said storage basket into position to rest upon the ice pieces discharged thereinto, a camming drive connection between said tray and said overfill arm for raising and lowering said overfill arm upon each operation of rotatably moving said tray, switch means controlling the filling and emptying of said metering device, a thermal element operative upon the freezing of the water in said ice tray to move said switch means into one position to effect filling of said metering device and the turning of said tray to a discharge position, a resistor heater for said thermal element, operative to heat said thermal element upon movement of said switch means to said one position to reset said thermal element and move said switch means to a second position, said switch means when in said second position being operative to operate said metering device to effect filling of the empty ice molds with water, and latch means operative by upward movement of said overfill arm to prevent movement of said switch means into said one position upon failure of said overfill arm to drop into said storage basket by the ice pieces discharged thereinto.

4. In an automatic icemaker, an oscillatable tray having oppositely facing ice molds in heat transfer relation with respect to each other, a metering device including a metering chamber having a movable wall portion movable in one direction by the pressure of water filling said chamber and movable in an opposite direction to expel water from said chamber, means driven by said movable wall portion for rotating said tray in one direction upon one operation of filling said chamber and in an opposite direction upon a second operation of filling said chamber, a storage basket in material receiving relation with respect to said tray, a pivoted overfill arm movable into said storage basket into position to rest upon the ice pieces discharged thereinto, a camming drive connection between said tray and said overfill arm for raising and lowering said overfill arm upon each operation of rotatably moving said tray, switch means controlling the filling and emptying of said metering device, a thermal element operative upon the freezing of the water in said ice tray to move said switch means into one position to effect filling of said metering device and the turning of said tray to a discharge position, a resistor heater for said thermal element, operative to heat said thermal element upon movement of said switch means to said one position to reset said thermal element and move said switch means to a second position, said switch means when in said second position being operative to operate said metering device to effect filling of the empty ice molds with water, and latch means operative by upward movement of said overfill arm to prevent movement of said switch means into said one position upon failure of said overfill arm to drop into said storage basket by the ice pieces discharged thereinto, comprising a catch normally in position to engage said switch means and prevent movement thereof into its first position, and moved out of position to engage said switch means each time same overfill arm drops to a lowermost position into said storage basket.

5. In an automatic icemaker, an oscillatable tray having oppositely facing ice molds in heat transfer relation with respect to each other, a metering device including a metering chamber having a movable wall portion movable in one direction by the pressure of water filling said chamber and movable in an opposite direction to expel water from said chamber, means driven by said movable wall portion for rotating said tray in one direction upon one operation of filling said chamber and in an opposite direction upon a second operation of filling said chamber, a storage basket in material receiving relation with respect to said tray, a pivoted overfill arm movable into said storage basket into position to rest upon the ice pieces discharged thereinto, a cam-

ming drive connection between said tray and said overfill arm for raising and lowering said overfill arm upon each operation of rotatably moving said tray, switch means controlling the filling and emptying of said metering device, a thermal element operative upon the freezing of the water in said ice tray to move said switch means into one position to effect filling of said metering device and the turning of said tray to a discharge position, a resistor heater for said thermal element, operative to heat said thermal element upon movement of said switch means to said one position to reset said thermal element and move said switch means to a second position, said switch means when in said second position being operative to operate said metering device to effect filling of the empty ice molds with water, and latch means operative by upward movement of said overfill arm to prevent movement of said switch means into said one position upon failure of said overfill arm to drop into said storage basket by the ice pieces discharged thereinto, comprising a resilient catch, a plunger engageable with said catch, a cam operated by said overfill arm upon raising and lowering movement of said overfill arm to move said plunger and thereby move said catch into position to engage said switch means and prevent operation thereof upon raising movement of said overfill arm, and into position to release said switch means upon lowering movement of said overfill arm.

6. In an automatic icemaker, an oscillatable ice tray having oppositely facing ice molds in heat transfer relation with respect to each other, an ice piece storage basket beneath said ice tray, metering means for filling the upwardly facing molds with a measured volume of water and loosening the ice pieces in the downwardly facing molds by the heat of the water filling the upwardly facing molds, power means actuated by the pressure of the water filling said metering means for moving said tray to bring the upwardly facing molds and the ice pieces therein into a downwardly facing release position, a pivoted overfill arm adapted to rest on the ice pieces in said storage basket, a camming connection between said tray and said overfill arm for raising and lowering said overfill arm in each direction of movement of said tray to a discharge position, a thermally responsive control device controlling the emptying and filling of said tray including a switch having a switch arm and two spaced stationary contacts, engaged by said switch arm in opposite directions of movement thereof, the engagement of said switch arm with one contact effecting the filling of said metering device and the turning of said tray to a discharge position, the engagement of said switch arm with the second contact effecting the filling of said tray with a measured volume of water, a thermally responsive element for operating said switch arm to engage said one contact upon freezing of the water in said tray, and operating said switch arm to engage said second contact upon the heating of said thermal element, means operated by said overfill arm to hold said switch arm from movement into said one position upon movement of said switch arm into an elevated position, and to release said switch arm upon lowering movement of said overfill arm.

7. In an automatic icemaker, an oscillatable ice tray having oppositely facing ice molds in heat transfer relation with respect to each other, an ice piece storage basket beneath said ice tray, metering means for filling the upwardly facing molds with a measured volume of water and loosening the ice pieces in the downwardly facing molds by the heat of the water filling the upwardly facing molds, power means actuated by the pressure of the water filling said metering means for moving said tray to bring the upwardly facing molds and the ice pieces therein into a downwardly facing release position, a pivoted overfill arm adapted to rest on the ice pieces in said storage basket, a camming connection between said tray and said overfill arm for raising and lowering

said overfill arm in each direction of movement of said tray to a discharge position, a thermally responsive control device controlling the emptying and filling of said tray including a switch having a switch arm and two spaced stationary contacts, engaged by said switch arm in opposite directions of movement thereof, the engagement of said switch arm with one contact effecting the filling of said metering device and the turning of said tray to a discharge position, the engagement of said switch arm with the second contact effecting the filling of said tray with a measured volume of water, a thermally responsive element for operating said switch arm to engage said one contact upon freezing of the water in said tray, and operating said switch arm to engage said second contact upon the heating of said thermal element, means operated by said overfill arm to hold said switch arm from movement into said one position upon movement of said switch arm into an elevated position, and to release said switch arm upon lowering movement of said overfill arm, comprising a resilient catch normally biased into position to catch said switch arm and hold said switch arm from engaging said one contact, and cam operated means movable upon lowering movement of said overfill arm to release said catch.

8. In an automatic icemaker, an oscillatable ice tray having oppositely facing ice molds in heat transfer relation with respect to each other, an ice piece storage basket beneath said ice tray, metering means for filling the upwardly facing molds with a measured volume of water and loosening the ice pieces in the downwardly facing molds by the heat of the water filling the upwardly facing molds, power means actuated by the pressure of the water filling said metering means for moving said tray to bring the upwardly facing molds and the ice pieces therein into a downwardly facing release position, a pivoted overfill arm adapted to rest on the ice pieces in said storage basket, a camming connection between said tray and said overfill arm for raising and lowering said overfill arm in each direction of movement of said tray to a discharge position, a thermally responsive control device controlling the emptying and filling of said tray including a switch having a switch arm and two spaced stationary contacts, engaged by said switch arm in opposite directions of movement thereof, the engagement of said switch arm with one contact effecting the filling of said metering device and the turning of said tray to a discharge position, the engagement of said switch arm with the second contact effecting the filling of said tray with a measured volume of water, a thermally responsive element for operating said switch arm to engage said one contact upon freezing of the water in said tray, and operating said switch arm to engage said second contact upon the heating of said thermal element, means operated by said overfill arm to hold said switch arm from movement into said one position upon movement of said switch arm into an elevated position, and to release said switch arm upon lowering movement of said overfill arm, a cam oscillatably driven by said switch arm upon raising and lowering movement thereof, a resilient catch biased to catch said switch arm and hold said switch arm from engaging said one contact, and a plunger operated by said cam to move said catch in a release position upon lowering movement of said switch arm.

9. In an automatic ice maker, an ice tray having ice molds therein, a storage tray in material receiving relation with respect to said ice molds, an overfill arm resting on the ice pieces discharged into said storage tray, means for raising and lowering said overfill arm during each cycle of discharge of ice pieces into said storage tray, metering means for filling the ice molds with a measured volume of water, switch means controlling the filling and emptying of said metering means, a thermal element operative upon the freezing of water in said molds to move said switch means into one position to effect filling of said metering means, a resistor heater for said thermal element, operative to heat said thermal element upon movement of said switch means to said one position to reset said thermal element and move said switch means to a second position, said switch means when in said second position being operative to operate said metering device to effect filling of the empty ice molds with water, and latch means operated by movement of said overfill arm and operative by upward movement of said overfill arm to prevent movement of said switch means into said one position upon failure of said overfill arm to drop into said storage basket.

10. In an automatic ice maker, an ice tray having ice molds therein, metering means for filling the ice molds with a measured volume of water, a storage tray in material receiving relation with respect to said ice molds, an overfill arm resting on the ice pieces discharged onto said storage tray, means for raising and lowering said overfill arm during each cycle of discharge of ice pieces into said storage tray, switch means controlling the filling and emptying of said metering means, a thermal element operative upon the freezing of water in said ice tray to move said switch means into one position to effect filling of said metering means, a resistor heater for said thermal element, operative to heat said thermal element upon movement of said switch means to said one position to reset said thermal element and move said switch means to a second position, said switch means when in said second position being operative to operate said metering means to effect filling of the empty ice molds with water, and latch means operated by said overfill arm upon upward movement thereof to prevent movement of said switch means into said one position upon failure of said overfill arm to drop into said storage basket, comprising a catch normally in position to engage said switch means and prevent movement thereof into its first position, and moved out of position to engage said switch means each time said overfill arm drops to a lowermost position into said storage basket.
